UNITED STATES PATENT OFFICE

FRANK P. WHITAKER, OF RUGBY, ENGLAND, ASSIGNOR TO GENERAL ELECTRIC COMPANY, A CORPORATION OF NEW YORK

ARC DISCHARGE DEVICE

Application filed March 12, 1932, Serial No. 598,517, and in Great Britain March 11, 1931.

My invention relates to arc discharge devices such as mercury arc rectifiers, more particularly to the construction of the shields for the anodes of these devices, and its principal object is the provision of an anode shield construction whereby the output of the devices is increased.

It is general practice in mercury arc rectifiers to provide each anode with a shield, which may take the form of a cylinder which surrounds the anode at its upper end and which is open at its lower end so that the arc can reach the anode. It has been proposed to provide an aperture in the side of this shield which is connected to a part of the rectifier which is efficiently cooled, so as to reduce the vapor pressure existing around the anode under certain conditions.

It has been further proposed, in an anode shield provided with one opening for the normal arc path between anode and cathode, to provide an additional opening or openings at the top or in the side of the shield, near the anode active surface and not shielded therefrom by baffles, the latter opening or openings being comparable in area with the opening for the normal arc path. In order that the arc might prefer to follow its normal path under usual load conditions, the additional opening or openings were provided with a high ratio of surface to area of opening to facilitate deionization of incoming mercury vapor.

In accordance with my present invention I provide an anode shield construction somewhat similar to the latter above described. In the present invention, however, the shield structure is used in conjunction with a special form of container. The anodes are mounted between an outer cylinder and an inner cylinder which extends a substantial distance below the anodes. The deionizing surfaces, which may be fins forming grilles or screens protecting the opening at the top of the cylinder, divide up the greater portion of the spaces or sectors allotted to each anode between the inside and the outside cylinders. The usual cylindrical shields may be dispensed with, the grilles or screens themselves

being depended on to subdivide the path for the arc.

My invention will be better understood from the following description when considered in connection with the accompanying drawing and its scope will be pointed out in the appended claims.

Referring to the drawing, Fig. 1 is a sectional view of an arc discharge device in which my invention has been embodied; Fig. 2 is a cross-sectional view on line 2-2 of Fig. 1; Figs. 3 and 4 are cross-sectional views illustrating modifications of the invention; Fig. 5 is a sectional view illustrating a further modification; and Fig. 6 is a cross-sectional view on line 6-6 of Fig. 5.

In Figs. 1 and 2, the numeral 1 represents a container or tank for a rectifier containing six anodes designated by the numerals 2 to 7. Each anode is provided with a shield 8 and with a plurality of deionizing fins or grille members 9 which divide up the space or sector, allocated to each anode, which is between the outer cylinder and an inner cylinder 10. These spaces or sectors may be divided off from each other by means of radial partitions 11 although in some cases these may be dispensed with. Openings 12 are formed in the upper portion of each shield 8 providing an additional path to the anode for the arc, the normal path of which comprises the opening at the bottom of the shield. The fins 9 extend downwardly from a point above the opening or openings 12 to a point a substantial distance below these openings and a substantial distance below the lower face of the anode, thus dividing up the greater portion of the space 13 allotted to each anode.

In the modification shown in Fig. 3, while the fins 9 are connected to the anode shield 8 as in Figs. 1 and 2, the fins are of different widths in order to divide up more completely the space allotted to the anode.

The deionizing fins may be connected to the anode shield 8 as shown in Figs. 1, 2 and 3 or they may be connected to the container 1 and inner cylinder 10 as shown in Fig. 4.

In the form of the invention illustrated in Figs. 1 and 2 as the anode shield 8 extends

- downwardly a substantial distance below the anode, the shield thus comprises a lower portion 14 below the additional arc openings 12 and inside the lower ends of fins 9. This 5 lower portion 14 of the anode shield may be omitted, however, as shown in Figs. 5 and 6. In the construction illustrated in the latter figures the shield 15 is short, the lower portion corresponding to portion 14 of Fig. 1 10 being dispensed with, radiating fins 16 being provided which extend below the lower face of the anode 12 and which may be provided with extensions 17 projecting inwardly below the anode.
- 15 It is preferable, in any of the modifications of the invention illustrated herein, to provide the radial partitions 11 between the tank 1 and inner cylinder 10 although these 20 partitions are not always absolutely essential.
- It will be readily understood that in any of the modifications of my invention herein described the grille or screen members may be so mounted as to be at the potential of the 25 container or tank 1, or they may be so mounted as to be insulated from the tank, for the purpose, for example, of connecting the grilles or screens to leads which are connected to a source of potential whereby the grille or 30 screen structures may be employed as grids or control electrodes to control the starting of the rectifier.
- The number of screen members or fins in each case and the distance between these 35 members should be so determined that arc-back is prevented.
- With an anode shield construction comprising the fin or grille arrangement above described in accordance with my invention 40 the size of the rectifier may be reduced as compared with those at present in use of equal power.
- It has hitherto been usual to deionize only the space inside the anode shield. With the 45 construction disclosed herein each sector of the tank may form the anode shield and each sector will be fitted with deionizing fins or grilles so that the customary anode shield may be omitted.
- 50 What I claim as new and desire to secure by Letters Patent of the United States is:
1. In an arc discharge device comprising an evacuated container and a cathode and anode mounted therein, an anode screen structure mounted in said container adjacent the active surfaces of said anode and comprising a plurality of relatively closely spaced arc sub-dividing elements extending in a direction laterally of the anode and a plurality 55 of arc sub-dividing elements extending in a direction downwardly of the anode, said screen structure providing relatively long and narrow passages throughout substantially all the space surrounding the active surfaces of 60 the anode.

2. In an arc discharge device comprising an evacuated container and a cathode and anode mounted therein, an anode screen structure mounted in said container adjacent the active surfaces of said anode and comprising 70 a series of relatively closely spaced fin-like elements having portions extending laterally of said anode and having other portions extending downwardly of said anode, said screen structure providing relatively long and 75 narrow passages throughout substantially all of the space surrounding the active surfaces of the anode.

3. In an arc discharge device comprising an evacuated container and a cathode and 80 anode mounted therein, an anode screen structure mounted in said container comprising a series of relatively closely spaced L-shaped fin-like members arranged edgewise to said anode and having a leg portion positioned 85 longitudinally of said anode and a foot portion positioned underneath said anode, said screen structure providing relatively long and narrow passages throughout substantially 90 all of the space surrounding the active surfaces of said anode.

4. In an arc discharge device comprising an evacuated container and a cathode and anode mounted therein, an anode screen structure mounted in said container comprising a plurality of relatively closely spaced fin-like members arranged edgewise to said anode and extending along the sides and underneath 95 said anode, said screen structure providing relatively long and narrow passages throughout substantially all of the space surrounding the active 100 surfaces of said anode.

In witness whereof, I have hereunto set my hand.
